DESIGN FOR A DENTAL LATHE

Gordon K. Cameron, Rochester, N. Y., assignor
to Ritter Dental Manufacturing Company, Inc.,
Rochester, N. Y., a corporation of Delaware

Application August 30, 1939, Serial No. 86,966

Term of patent 14 years

To all whom it may concern:

Be it known that I, Gordon K. Cameron, a citizen of the United States, residing at Rochester, in the county of Monroe and State of New York, have invented a new, original, and ornamental Design for a Dental Lathe, of which the following is a specification, reference being had to the accompanying drawing, forming part thereof.

Fig. 1 is a front elevation of the dental lathe of my invention;

Fig. 2 is a side elevation of the same.

I claim:

The ornamental design for a dental lathe, substantially as shown.

GORDON K. CAMERON.
